[57] CLAIM

The ornamental design for a smokers deterrent judge's gavel and ashtray, as shown and described.

DESCRIPTION

FIG. 1 is a perspective view of a smokers deterrent judge's gavel and ashtray, showing my new design.

FIG. 2 is a side elevational view thereof;

FIG. 3 is a rear elevational view thereof;

FIG. 4 is a front elevational view thereof;

FIG. 5 is a top plan view thereof.

The lettering has been partially shown in FIG. 1 for ease of illustration.
